(57) **CLAIM**

We claim the ornamental design for a handbag with opening flap and drink pouch, as shown and described.

DESCRIPTION

FIG. 1 is a perspective view of a handbag with opening flap and drink pouch showing our new design.

FIG. 2 is a front elevational view thereof with the opening flap in its closed position.

FIG. 3 is a rear elevational view thereof.

FIG. 4 is a left side elevational view thereof with the opening flap in its closed position.

FIG. 5 is a right side elevational view thereof with the opening flap in its closed position.

FIG. 6 is a top planform view thereof with the opening flap in its closed position.

FIG. 7 is a bottom planform view thereof with the opening flap in its closed position.

FIG. 8 is a top planform view thereof with the opening flap in its open position.

FIG. 9 is a top planform view thereof with the opening flap in its open position and with the handbag open showing three separate compartments, one of which having a second flap in its closed position.

FIG. 10 is a top planform view thereof similar to FIG. 9 showing the second flap in its open position.

FIG. 11 is a right side elevational view thereof showing the side zipper open and showing access to two compartments.

FIG. 12 is a right side elevational view thereof similar to FIG. 11 showing the positioning of a drinking bag spout.

FIG. 13 is a cross-sectional view thereof taken along line 13-13 of FIG. 8 showing one of the three compartments of FIGS. 9 and 10 with the second flap in its closed position.

FIG. 14 is a cross-sectional view thereof similar to FIG. 13 with the second flap in its open position; and,

FIG. 15 is a cross-sectional view thereof taken along line 15-15 of FIG. 8 showing another one of the three compartments of FIGS. 9 and 10.

The broken lines showing a strap and a typical drinking bag spout are for illustrative purposes only and form no part of the claimed design.

The broken lines showing a portion of a drinking straw are for the purpose of illustrating environment and form no part of the claimed design.
